(57) **CLAIM**

The ornamental design for a display panel with animated graphical user interface, as shown and described.

DESCRIPTION

The patent or application file contains at least one drawing executed in color. Copies of this patent or patent application publication with color drawing(s) will be provided by the Office upon request and payment of the necessary fee.

1. Display panel with animated graphical user interface

1.1 : Front

1.2 : Second image

1.3 : Third image

1.4 : Fourth image

The appearance of the transitional image sequentially transitions between the images shown in Reproductions 1.1-1.4; the process or period in which one image transitions to another image forms no part of the claimed design; reproduction 1.1 is a front view showing a first image before change; reproduction 1.2 is a second image view showing a rotated state to the left from the state of reproduction 1.1; reproduction 1.3 is a third image view showing a rotated state to the left from the state of reproduction 1.2; reproduction 1.4 is a fourth image view showing a rotated state to the left from the state of reproduction 1.3; the dash-dash broken lines represent the display panel and form no part of the claimed design; the dot-dash broken lines represent a boundary encircling the reproductions and form no part of the claimed design.
